(57) **CLAIM**

The ornamental design for a telescope, as shown and described.

DESCRIPTION

1. Telescope
2. Telescope
- 1.1 : Perspective view 1
- 1.2 : Perspective view 2
- 1.3 : Front
- 1.4 : Back
- 1.5 : Right
- 1.6 : Top
- 1.7 : Bottom
- 1.8 : Left
- 2.1 : Perspective view 1
- 2.2 : Perspective view 2
- 2.3 : Front
- 2.4 : Back
- 2.5 : Right
- 2.6 : Top
- 2.7 : Bottom
- 2.8 : Left

The broken lines shown in the drawings depict portions of the telescope that form no part of the claimed design.

1 Claim, 16 Drawing Sheets(56)
